REGENERATIVE HEAT EXCHANGER

Henry Cohen, Newcastle-upon-Tyne, and Arthur Rynyon Devereux Robson, Peterborough, England, assignors to Power Jets (Research and Development) Limited, London, England, a British company

Application August 23, 1948, Serial No. 45,756
In Great Britain September 9, 1947

4 Claims. (Cl. 257—6)

1

This invention relates to regenerative heat exchangers of the kind wherein a heat transmitting and absorbing matrix in disc or drum form is adapted to rotate successively through one chamber containing a fluid at a higher temperature and a second chamber containing another fluid at a lower temperature, so as to absorb heat from the former and transmit it to the latter.

According to the present invention a regenerative heat exchanger of the kind described is provided with two matrix discs so arranged in conjunction with the dividing and sealing members and with the casing that the casing is formed into three chambers for each of the fluid flow paths, one of each of which is centrally situated between the two discs while the other two are situated each between a face of a disc and an adjacent end wall of the casing. The purpose of this arrangement is to enable the entry and leaving ducts of the high and lower temperature fluids to be so arranged in conjunction with the two discs that the lower temperature fluid enters through two of the outer chambers and passes through the discs to leave by a central chamber while the high temperature fluid enters the other central chamber and passes through the discs to leave by the other two outer chambers. The dividing and sealing members may be arranged to be guided in slots in the casing and end walls to allow for their movement normal to the face of the matrix discs and for maintaining a seal at the edges of the members adjacent the casing and the walls. Each member may be provided with rollers which are adapted to bear against a face of the matrix disc, the periphery of each of which rollers may project slightly beyond the edge of the member adjacent that face so that when the members are urged towards the face of the matrix, e. g. by means of a spring or other resilient means, a small and definite clearance is maintained between the said edge of the member and the face of the disc.

In the preferred construction according to the invention there are three dividing and sealing members of which one is arranged diametrically between the two discs and the other two are arranged in the same plane as the central member between a disc and the casing. The dividing and sealing member between the two discs may be fixed to the casing while the discs and the other two members are movable in an axial direction.

The effect of the general arrangement of the

2

ducting as described above, is to maintain the outer chambers, the bearings for the discs and the spring or other resilient means urging the movable dividing members and discs axially at a relatively low temperature while the central chambers are at a relatively higher temperature, this being generally advantageous from the mechanical point of view, and in particular for retaining the resilience of any springs used in the construction.

In an alternative form of construction the above-mentioned strips may be of ceramic material instead of metal.

The invention will now be described by way of example only with reference to the accompanying drawings of which the single figure is a divided and sectioned perspective view of a regenerative heat exchanger with sealing or dividing members or plates and rotatable matrix discs.

20 In the figure a regenerative heat exchanger has an outer cylindrical casing 10 with tangentially arranged fluid inlet and outlet connections; two inlets 11 and 12 and one outlet 13 for the cold high pressure fluid and one inlet 14 and 25 two outlets 15 and 16 for the hot low pressure fluid. The cylindrical casing is provided with removable end covers 17 and 18.

Two similar porous matrix members 19 and 20 of disc form are mounted for rotation within the casing 10 on a shaft 21. They are splined to the shaft 21 (splines not shown) and are capable of relative axial movement on the splines. The end covers 17 and 18 are provided with bearing bosses 24 and 25 respectively in which

30 bearings 22 and 23 are located respectively to support the matrix carrying shaft 21. The disc members 19 and 20 divide the casing 10 into three chambers and each chamber is divided diametrically by sealing or dividing members or plates 26, 27 and 28 which are supported in

35 grooves or slots 29 or 30 formed respectively in the casing 10 and covers 17 and 18. The two sealing or dividing plates 26 and 28 adjacent the covers 17 and 18 are spring urged towards one another by compression springs 31 and 32 ar-

45 ranged around the shaft 21 between the covers 17 and 18 and the plates 26 and 28 respectively. The two matrix discs 19 and 20 are sandwiched between the central dividing plate 27 and the two sealing or dividing plates 26 and 27. Hollow

50 bosses 33, 34 and 35 are formed respectively on the sealing or dividing plates 26, 27 and 28 through which the shaft 21 passes. The bosses 33, 34 and 35 closely engage the matrix discs 55 and the end covers 17 and 18 to prevent any

leakage between the high and low pressure chambers. The bosses 33 and 35 are arranged to receive the springs 31 and 32 respectively.

The matrix discs 19 and 20 are each formed of a corrugated strip 36 and a plain strip 37 of metal wound in a spiral on a central boss 38. A rim member 39 is placed around the spirally arranged strips 36 and 37. A labyrinth gland (not shown) may be machined on the outer surface of the rim 39. The sealing or dividing plates 26, 27 and 28 may be arranged to rub against the matrix discs 19 and 20 to form the diametrical seal or they may be provided with carbon rollers 9 at their ends adjacent the periphery of the discs 19 and 20 to roll against the rim 39. The rollers 9 are arranged to be slightly proud of the face of the sealing or dividing plates 26, 27 and 28 so that a minute clearance is maintained between the face of the discs and the face of the sealing or dividing plates.

We claim:

1. A regenerative heat exchanger comprising a cylindrical casing, a shaft extending axially through said casing and supported in bearings in the ends of said casing, a pair of rotatable heat absorbing and heat transmitting cellular matrix discs spaced apart on said shaft within said casing and dividing it into three chambers, sealing and dividing members diametrically arranged in said casing between said discs and between said discs and said ends of said casing dividing said chambers into two separate groups of chambers, one group for the passage of a high temperature fluid and the other group for a lower temperature fluid, the high temperature group being provided with a fluid inlet to the central chamber and with fluid outlets in each of the two outer chambers and the lower temperature group being provided with a fluid outlet from the central chamber and fluid inlets in each of the two outer chambers.

2. A regenerative heat exchanger comprising a cylindrical casing, a shaft extending axially through said casing and supported in bearings in the ends of said casing, a pair of rotatable heat absorbing and heat transmitting cellular matrix discs spaced apart on said shaft within said casing and dividing it into three chambers, sealing and dividing members diametrically arranged in said casing between said discs and between said discs and said ends of said casing dividing said chambers into two separate groups of chambers, one group for the passage of a high temperature fluid and the other group for a lower temperature fluid, the high temperature group being provided with a fluid inlet to the central chamber and with fluid outlets in each of the two outer chambers and the lower temperature group being provided with a fluid outlet from the central chamber and fluid inlets in each of the two outer chambers, and resilient means urging said sealing and dividing members together to engage said discs between them to maintain a seal between said high and lower temperature fluids.

3. A regenerative heat exchanger comprising a cylindrical casing, a shaft extending ax-

ially through said casing and supported in bearings in the ends of said casing, a pair of rotatable heat absorbing and heat transmitting cellular matrix discs spaced apart on said shaft within said casing and dividing it into three chambers, sealing and dividing members diametrically arranged in said casing between said discs and between said discs and said ends of said casing dividing said chambers into two separate groups of chambers, one group for the passage of a high temperature fluid and the other group for a lower temperature fluid, the high temperature group being provided with a fluid inlet to the central chamber and with fluid outlets in each of the two outer chambers and the lower temperature group being provided with a fluid outlet from the central chamber and fluid inlets in each of the two outer chambers, rollers on said sealing and dividing members, each with their periphery projecting slightly beyond the edges of said members adjacent said discs to engage said discs and resilient means urging said sealing and dividing members together to maintain said rollers in contact with said discs to maintain a seal with a small gap.

4. A regenerative heat exchanger comprising a cylindrical casing, a shaft extending axially through said casing and supported in bearings in the ends of said casing, a pair of rotatable heat absorbing and heat transmitting cellular matrix discs spaced apart on said shaft within said casing and dividing it into three chambers, sealing and dividing members diametrically arranged in said casing between said discs and between said discs and said ends of said casing dividing said chambers into two separate groups of chambers, one group for the passage of a high temperature fluid and the other group for a lower temperature fluid, the high temperature group being provided with a fluid inlet to the central chamber and with fluid outlets in each of the two outer chambers and the lower temperature group being provided with a fluid outlet from the central chamber and fluid inlets in each of the two outer chambers, and resilient means on said shaft between said casing ends and said adjacent sealing and dividing member urging said sealing and dividing members together axially to engage said discs between them to maintain a seal between said high and lower temperature fluids.
